UNITED STATES PATENT OFFICE.

HAROLD AUBREY JOHNSON, OF BRISTOL, ENGLAND.

APPARATUS FOR SYNCHRONIZATION.

Application filed November 2, 1921. Serial No. 512,290.

To all whom it may concern:

Be it known that I, HAROLD AUBREY JOHNSON, of 81 Dongola Road, Bishopston, Bristol, England, a subject of the King of Great Britain and Ireland, have invented certain new and useful Improvements in Apparatus for Synchronization, of which the following is a specification.

This invention relates to synchronizing apparatus and more particularly to apparatus for synchronizing notes or word sounds given out by gramophones, phonographs and other mechanically operated musical instruments with movements and motions represented on cinema screens.

The object of this invention is to provide an improved apparatus which will attain this end.

Apparatus made in accordance with this invention is characterized by the features set forth in the following claims, and is exemplified by the following description, reference being had to the accompanying drawings, in which:

Fig. 1 is a plan of one form of apparatus made in accordance with this invention;

Fig. 2 is an elevation of Fig. 1 looking in the direction of arrow A, with the sprocket removed;

Fig. 3 is a sectional elevation taken on the line B—B of Fig. 1 looking in the direction of arrow C;

Fig. 4 is a sectional elevation taken on line B—B of Fig. 1 looking in the direction of arrow D;

Fig. 5 is an elevation of Fig. 1 looking in the direction of arrow E;

Fig. 6 is a sectional elevation taken on line F—F of Fig. 1 looking in the direction of arrow G.

Fig. 7 is a diagrammatic ensemble drawing of the cinematograph, synchronizing apparatus and gramophone.

On the base *a* of the synchronizing apparatus is mounted a spindle *b* in bearings *c d*. Near one end of the spindle *b* is a ratchet wheel *e*. The other end of the spindle *b* is screw threaded at *f*. Engaging with thread *f* is a threaded sleeve *g* integral with a toothed wheel *h*. A coil spring *j* on the spindle *b* is anchored to the ratchet wheel *e* at *k* and to the sleeve *g* at *m*. On the base *a* is mounted a spindle *n* in bearings *o o*. The spindle *n* carries a governor *p* and a worm *q*. The worm *q* is driven from the

shaft *r* through the toothed wheels and pinion *t* and worm *v*, and the toothed wheel *h* is driven by a pinion *w* on the shaft *r*. On the spindle *n* is a brake disc *x* which is adapted to be moved in the direction of the dotted arrow when the governor *p* acts under centrifugal force.

On the base *a* is disposed a guide *2* in which is mounted a sliding yoke *3* the position of which is adapted to be adjusted by a bolt *4* mounted in a bearing *5* and engaging a thread in the yoke *3*. In the yoke *3* is pivoted a bell-crank lever *6, 7*. The arm *7* carries brake blocks *8* adapted to bear on the disc *x* and the arm *6* carries an adjustable extension *9* provided with a stud *10*. On the bed *a* is mounted a rack *11* adapted to engage with a pinion *12* which carries a pointer or indicator *13*. The rack *11* is provided with an anti-friction roller *14* adapted to bear against the face of the toothed wheel *h*, and an arm *15* provided with a slot *16* which coacts with the stud *10* on the extension *9*. On the bed *a* is mounted an electro-magnet *17* provided with terminals *18*. The armature *19* is pivotally mounted on a forked bracket *20*. The armature carries a pawl *21* extending over and coacting with the ratchet wheel *e*. A coil spring *22* effects the return of the pawl *21* and a coil spring *23* on the spindle of the pinion *12* keeps the roller *14* against the face of the toothed wheel *h*.

The turn table of the gramophone or other rotary part of the musical instrument is provided with a commutator which is put in circuit with the electro-magnet *17*, a switch and a source of electric supply.

A scale *24* is mounted on the bed *a* below the pointer *13*.

In operation a sprocket wheel *25* on the spindle *r* is set in motion by the operation of the cinematograph *26* by means of a chain drive *27*, and the gramophone or other mechanically operated musical instrument *28* is also set in motion. The rotation of the spindle *r* rotates the toothed wheel *h* and applies a turning effort to the ratchet wheel *e* through the coil spring *j*.

The operation of the electro-magnet *17* releases the ratchet wheel *e* step by step. It is arranged that the motive power driving the spindle *r* will tend to make the toothed wheel *h* rotate faster than the ratchet wheel *e*. But immediately the toothed wheel *h*

does rotate faster than the ratchet wheel *e* it slides along the spindle *b* causing the rack 11 to slide with it and operating the bell-crank lever 6, 7 which applies the brake 5 blocks 8 to the disc *x* and retards the cinematograph through the medium of the chain drive 27. Should the cinematograph be temporarily retarded to such an extent that the toothed wheel *h* rotates slower than the 10 ratchet wheel *e* is allowed to rotate by the pawl 21, the spring *j* will uncoil and keep the ratchet wheel rotating at its full speed while the toothed wheel *h* will slide in the direction which will cause the pressure of 15 the brake blocks 8 against the disc *x* to be lessened. The said pressure will continue to diminish until the cinematograph again synchronizes with the gramophone. The disc *x* is applied to the brake blocks 8 by 20 the governor *p* if the speed of the sprocket wheel 25 exceeds a predetermined velocity.

The position of the indicator 13 on the scale 24 and the position of the film with respect to the music can be adjusted by altering 25 the position of the sliding yoke 3 by the screwed bolt 4 which changes position of the brake 8.

What I claim and desire to secure by Letters Patent is:—

30 1. Apparatus for automatically maintaining a predetermined ratio between the working speeds of two machines, said apparatus comprising an electric circuit in which impulses are produced by the rotation of one 35 of the machines, a member rotated by the other of the two machines, a member whose rate of rotation is adapted to be governed by the impulses produced in the electric circuit said two last mentioned members being 40 adapted to rotate at equal speeds when the ratio between the working speeds of the two machines is the predetermined ratio, and a spring connecting the two last mentioned members whereby motion may be lost or 45 gained between them, means whereby any differences of speed between the two last mentioned members cause one of them to move laterally, a retarding brake adapted to be continuously applied to rotating parts in 50 mechanical connection with one of the two machines, and means whereby the said lateral movement of the one member alters the pressure of the retarding brake so that the speed at which the braked machine is working is altered until the predetermined ratio between the working speeds of the two machines is attained.

55 2. Apparatus for automatically maintaining a predetermined ratio between the working speeds of two machines, said apparatus comprising an electric circuit in which impulses are produced by the rotation of one of the machines, a member rotated by the other of the two machines, a member 60 whose rate of rotation is adapted to be gov-

erned by the impulses produced in the electric circuit said two last mentioned members being adapted to rotate at equal speeds when the ratio between the working speeds of the two machines is the predetermined ratio, and a spring connecting the two last mentioned members whereby motion may be lost or gained between them, means whereby any differences of speed between the two last mentioned members cause one of them to move laterally, a retarding brake adapted to be continuously applied to rotating parts in mechanical connection with one of the two machines, means whereby the said lateral movement of the one member alters the pressure of the retarding brake so that the speed at which the braked machine is working is altered until the predetermined ratio between the working speeds of the two machines is attained, means whereby the said lateral movement of the one member actuates a pointer to move along a graduated scale, means whereby the braked machine may be caused to accelerate or retard its speed of working for a short interval of time without altering the speed of the other machine, and means whereby after said acceleration or retardation the braked machine is automatically controlled so as to maintain the predetermined ratio between the working speeds of the two machines.

95 3. Apparatus for automatically governing the speed of rotation of one machine in such a manner as to maintain its speed at a predetermined constant proportion to that of a second machine, said means comprising a commutator on the latter machine, an electric circuit adapted to be interrupted by the commutator, a gear wheel mechanically rotated by the governed machine, a ratchet wheel whose rotation is controlled by the interruptions of the electric circuit, said gear wheel and ratchet wheel being adapted to rotate at equal speeds when the speed of rotation of the governed machine is the predetermined proportion of that of the other machine, a spindle on which the gear wheel and ratchet wheel are mounted one of them being keyed to the spindle and the other adapted to screw loosely onto a threaded portion of the spindle, a helical spring connecting the gear wheel and ratchet wheel said spring being coiled round the spindle whereby motion may be lost or gained between the ratchet wheel and gear wheel, means whereby a difference of speed between the gear wheel and ratchet wheel causes one of them to move laterally, a retarding brake adapted to be continuously applied to rotating parts in mechanical connection with one of the two machines, a connecting link disposed between the retarding brake and the laterally moving wheel so that the lateral movement of the wheel increases or lessens the pressure of the retarding brake so as to maintain the 100 105 110 115 120 125 130

speed of the governed machine at the predetermined proportion of the other machine, and means for altering the effective length of the connecting link between the retarding 5 brake and the laterally moving wheel, whereby the speed of rotation of the governed machine may be accelerated or retard-

ed for a short interval of time without altering the speed of rotation of the other machine.

10

In testimony whereof I have signed my name to this specification.

HAROLD AUBREY JOHNSON.
